[57] CLAIM

The ornamental design for a plug-mounted background noise amplifier, as shown and described.

DESCRIPTION

FIG. 1 is a top plan view of a plug-mounted background noise amplifier showing our new design;

FIG. 2 is a sectional view thereof, taken along line 2—2 of FIG. 1;

FIG. 3 is a front elevational view thereof;

FIG. 4 is a bottom plan view thereof;

FIG. 5 is a sectional view thereof, taken along line 5—5 of FIG. 1;

FIG. 6 is a right side elevational view thereof;

FIG. 7 is a rear elevational view thereof; and

FIG. 8 is a left side elevational view thereof.

FIG. 1

FIG. 6

FIG. 2

FIG. 3

FIG. 4
